MEANS FOR SECURING BAILS TO SMOKE-
STANDS FOR SHIPMENT

Gordon A. Gilbertson, Chicago, Ill., assignor to
Talbert M. Dick, as trustee of the Cadet
Smokestands Company, Des Moines, Iowa, a
common-law trust

Application August 15, 1940, Serial No. 352,775

3 Claims. (Cl. 206—47)

The principal object of this invention is to provide a successful, economical means of securing a handle bail to a smokestand or like in "knocked-down" condition for packaging purposes.

A further object of this invention is to provide a method of securing detachable bails to smokestands or the like for boxing or shipping purposes, whereby the handle bail will be secured to the smokestand or like against accidental loss in non-assembled condition, and without danger of marring or scratching the finish of the smokestand or like.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

Fig. 1 is a perspective view of my handle bail holding member showing by dotted lines a smokestand and a bail successfully secured together by the same.

Fig. 2 is an enlarged cross sectional view of a portion of the base of a smokestand with my bail enclosing envelope secured thereon.

Many smokestands have handle bails. In many cases these handle bails are detachable from the urn portion of the smokestand in order to reduce the height of the smokestand for packaging and shipping purposes. Not only is a smaller package possible by the removal of the handle bail, but there is less chance of damaging the smokestand in storage or shipment, and by virtue of the handle bail being detached from the smokestand, a cheaper transportation charge is possible under the rule of "knocked-down" merchandise. The chief objection, however, to the packaging and shipment of smokestands that must be later assembled is that these handle bails often are lost, are not noticed in the package by the one unpacking the smokestand, and in many instances are loose in the package and mar and scratch the fine finish of the smokestand. I have overcome such objections by providing a unique envelope that successfully holds the detached bail to and around the column or stem of the smokestand.

Referring to the drawing, I have used the numeral 10 to generally designate an ordinary smokestand having a column portion 11, an enlarged urn portion 12 on the upper end of the column, and an enlarged base 13 on the lower

end of the column. Such smokestands are very common and usually have a detachable bail 14 which, as is well known, snaps into place on the urn portion 12 by having its ends engage depressions or slot openings 15 in the urn 12. These smokestands have their urn portion, base portion, and column portion rigidly bolted together by an elongated bolt element 16.

My method of securing a bail 14 to the smokestand 10 for packaging purposes consists of an envelope 17 having the usual flap 18 capable of closing its open end as shown in Fig. 1. The numeral 19 designates a hole extending completely through the central area of the envelope.

15 In practice, I first placed the bail 14 inside the envelope 17 as shown by dotted lines in Fig. 1. Such handle bails 14 are curved and therefore partially embrace in spaced relationship the hole 19 extending through the envelope. At the time the smokestand is assembled at the factory, the column 11 is inserted through the hole 19. Obviously after the smokestand is assembled by the bolt 16, the envelope 17 cannot become accidentally detached from the column 11 by virtue

20 of the fact of the urn portion 12 on one end of the column and the base 13 on the other end of the column. The bail 14 is secured inside the envelope by folding the flap to a closed position and stapling it closed with a staple 20. This 25 staple 20 pieces the flap and envelope at a point inside the circular bail 14 as shown in Fig. 1, thereby preventing undesirable movement of the bail 14 inside the envelope. The envelope is of such dimensions as to closely fit the bail 14 and therefore the bail 14 cannot move any substantial distance within the envelope 17 and engage and mar the finish of the column 11. The paper or like envelope 17 will hold and insulate the metallic bail 14 from any engagement with

30 any part of the smokestand proper. Obviously anyone unpacking the smokestand cannot avoid discovery of the existence of the detachable bail 14 on the smokestand if between the base and urn. On the other hand, if the bail were concealed within the base or within the urn, or it were merely loose within the shipping package, it might not be found by the one unpacking the smokestand. As the envelope 17 is made of tearable material, it is merely necessary to tear 35 or cut the envelope from the column 16, obtain the handle bail therein and assemble the same on the top portion of the smokestand.

40 From the foregoing, it will readily be seen that I have provided an economical and successful means and method of securing a detachable bail 45

in "knocked-down" condition to a smokestand for shipping purposes, wherein the bail cannot become detached or lost nor mar or damage the smokestand while in transit.

Some changes may be made in the construction and arrangement of my improved method of and means for securing a bail to a smokestand for shipment without departing from the real spirit and purpose of my invention, and it is my intention to cover by my claims any modified forms of structure or use of mechanical equivalents which may be reasonably included within their scope.

I claim:

1. In a shipping package for a smoking stand having a base, a vertical column, an urn portion and a semi-circular detachable bail, the improvement which comprises an envelope with a central opening therein through which the vertical column extends; the detachable bail being positioned within the envelope, and a means for confining said bail in said envelope substantially concentric relative with said column. 15 20

2. In a shipping package for a smoking stand having a base, a vertical column, an urn portion, and a detachable bail, the improvement which comprises a tearable envelope with an opening therein through which the vertical column extends; said detachable bail being positioned within said envelope and said envelope being of such dimensions as to closely fit the bail and hold said bail in spaced relationship to said column.

3. In a shipping package for a smoking stand having a base, a vertical column, an urn portion and a semi-circular detachable bail, the improvement which comprises an envelope with a central opening therein through which the vertical column extends; the detachable bail being positioned within the envelope, and a means for closing said envelope and holding said bail in spaced relationship relative to said column.

GORDON A. GILBERTSON.
